UNITED STATES PATENT OFFICE.

WILLIAM R. BISHOP AND RYLAND W. EAMES, OF COLUMBUS, COLORADO.

ELEVATED ENDLESS SINGLE-TRACK RAILWAY.

SPECIFICATION forming part of Letters Patent No. 288,400, dated November 13, 1883.

Application filed August 2, 1882. (No model.)

To all whom it may concern:

Be it known that we, WILLIAM R. BISHOP and RYLAND W. EAMES, of Columbus city, in the county of Chaffee and State of Colorado, 5 have invented a new and Improved Elevated Endless Single-Track Railway, of which the following is a full, clear, and exact description.

Our invention consists of an endless elevated single-rail railway upon which cars are to be 10 operated by an endless cable.

The object of our invention is, first, cheapness of construction in using a single rail; second, durability by relieving the cable of all unnecessary weight by suspending the load 15 from a car upon the track, instead of being attached to the cable; third, to produce a rotary tramway, thereby increasing the capacity of its performance.

Our invention also consists of a kind of expansion-joint in the endless railway spoken of, 20 the object of which is to allow the drum, where the cable reverses at the end of the road, to shift forward and backward as the length of the cable changes, to thereby preserve the 25 proper tension at all times.

Our invention further consists of an automatic gravity-brake constructed to act by the effect of the incline of the road. The object of this feature of the invention is to further 30 relieve the cable of unnecessary strain, the cable only being used to haul up the empty cars, the loaded cars braking themselves down the steep incline of the road, all as hereinafter fully described, and pointed out in the 35 claims.

Reference is to be had to the accompanying drawings, forming part of this specification, in which similar letters of reference indicate corresponding parts in all the figures.

40 Figure 1 is a side elevation of the lap-joint contrivance for regulating the tension of the endless cable. Fig. 2 is a plan view of the same. Fig. 3 is a cross-section of the track. Fig. 4 is a side elevation, showing the automatic brake attached to each car; and Fig. 5 is a plan view of the brake contrivance of the drum around which the endless cable reverses 45 at the end of the line.

The main way consists of the T-rails *a*, attached to the outer sides of the timbers *b*, mounted each side of the top of an elevated structure of any approved kind, of which *c*

represents the top cross-timbers supporting the said stringers *b* and the rails thereon, and *d* the posts supporting said cross-timbers. 55

The cars consist of frames *e f*, of any approved kind, having upper and lower wheels, *g h*, grooved to fit the upper and lower sides of the rail, and so fitted to the rail that the flanges of the grooves of the wheels, together 60 with the load-carrier *d'*, suspended below the cars by a rod, *i*, secure the cars on the rails.

The cars are attached to an endless wire cable, *j*, which is itself suspended by the cars, so as to prevent sagging, except between the cars, 65 and this cable passes around drums *m* at each end of the way, for returning the cars to the starting-point. These drums are provided with powerful brake devices, consisting of a brake wheel or drum, *n*, against which brake- 70 shoes *o*, attached to beams *p*, are powerfully drawn by the levers *q*, chains *r*, and hand wheel and shaft *s*, to control the speed of the cars. We propose to mount one of these 75 drums—say at the ore-house—on a kind of lap-joint of the track or way, so that it can shift backward and forward as the cable lengthens and shortens, and thereby enable the cable to have uniform tension at all times.

For this purpose we mount the drum *m* on a frame, *t*, which 80 is itself mounted on rollers *u*, working on another short and permanently-fixed track, *w*, below, so that said frame *t* can shift along said track a short distance each way, and to one end of the frame we attach a chain, *x*, and a 85 heavy weight, *y*, to maintain the tension of the cable. On the upper part of said frame *t*, but below the terminal sections of the rails *a*, we locate other rails, *a'*, sufficiently lower than rails *a* to enable the lower wheels, *h*, of the 90 cars to run on them, and the timbers *b*, extending over frame *t*, are supported on rollers *b'*, resting on frame *t*. This, together with timbers *b'* of the extension-frame, and overlapping the terminal part of the permanent way, forms the 95 lap by which the cars pass from permanent rails *a* to extension-rails *a'*, enabling the drum *m* to shift forward and backward as the cable lengthens and shortens.

For the automatic gravity-brake contrivance, we attach the arm *c'* to the rod *i*, by which the bucket is suspended from the car, and connect said arm with brake-levers *e* by rod *f'*, said levers being pivoted at *g'*, so as to 100

bear the brakes h' on the wheels, whereby the 5 inclination of the car on an incline descending toward the left hand of the drawing, the bucket remaining in a vertical line, depresses said levers e' with respect to the car. The spring i' releases the brakes when the car assumes a level position, and it will be seen that when the car turns around at the end of the road and returns uphill the weight will keep the brakes 10 off the wheels. Moreover, the amount of the depression of the brakes varies in proportion to the inclination of the descent, so that the steeper the grade is the harder the brakes will bear. 15 The car-frame $e f$ is jointed to afford ample freedom of movement of the wheels around the curved tracks at the drums, and the buckets or carriers d' have self-dumping bottoms, to be unlatched for opening, and to be closed and latched automatically by suitable trip-levers 20 and standards fixed at any desired point on the line.

Having thus fully described our invention, we claim as new and desire to secure by Letters Patent—

- 25 1. In an endless single-track railway, the combination, with an endless cable, of drums around which the cable passes, brake devices for said drums, and means for applying the same, substantially as herein shown and described.
2. In an endless single-track railway, the combination, with the main track, of a movable frame carrying one of the drums around which the endless cable passes, and provided with a 30 track forming a lap-joint with said main track, substantially as herein shown and described.

3. In an endless single-track railway, the combination, with the main track, of a movable frame carrying one of the drums around which the endless cable passes, and provided 40 with a track forming a lap-joint with the main track, and a chain attached to said frame, and provided with a weight at its end, substantially as herein shown and described.

4. In an endless single-track railway, the 45 combination, with the drums m , provided with the brake-wheels n , of the brake-shoes o , the levers q , the chains r , and hand-wheels s , substantially as herein shown and described.

5. In an endless single-track railway, the 50 combination, with the tracks $a w$, of the frame t , provided with track a' and wheels u , and carrying one of the drums m , the chain x , and weight y , substantially as herein shown and described.

6. In an endless single-track railway, the combination, with the tracks $a w$, of the frame t , provided with the track a' and the wheels $b' u$, and carrying one of the drums m , the chain x , and weight y , substantially as herein 55 shown and described.

7. In an endless single-track railway, the combination, with the carriage $e f g h$ and the carrier d' , suspended therefrom by rod i , of the arm c' , the rod f' , brake-levers e' , brakes h' , and spring i , substantially as herein shown and described.
